UNITED STATES PATENT OFFICE.

HOWARD DOUGLAS HODGE, OF WALTHAM ABBEY, ENGLAND, ASSIGNOR TO NOBEL'S EXPLOSIVES COMPANY, LIMITED, OF GLASGOW, SCOTLAND.

MACHINE FOR DRYING FRESHLY-PRINTED CYLINDRICAL ARTICLES, SUCH AS CARTRIDGE-SHELLS.

1,089,706.

Specification of Letters Patent. Patented Mar. 10, 1914.

Application filed December 31, 1912. Serial No. 739,450.

To all whom it may concern:

Be it known that I, HOWARD DOUGLAS HODGE, a citizen of the United States, residing at Joyce House, Waltham Abbey, Essex, England, have invented a new and useful Machine for Drying Freshly-Printed Cylindrical Articles, Such as Cartridge-Shells, of which the following is a specification.

The object of this invention is to provide a machine for drying freshly printed cylindrical articles especially those made of highly glazed paper or the like such as the shells of cartridges. With such articles the ink takes a very long time to dry and it is essential that the articles should be supported for a long time in such a way that they cannot be rubbed and the ink therefore cannot smear.

A machine embodying my invention and suitable for drying articles, such as cartridge shells, which have enlarged heads as shown in the accompanying drawings,—Figure 1 being a side elevation, and Fig. 2 a plan, Fig. 3 showing a detail.

1 is the main shaft of the machine driven by a belt pulley 2. A chain 3 passing over a sprocket wheel 4 on this shaft drives a sprocket wheel 5 on a shaft 6 on which is an interrupted worm 7 imparting a step by step movement of rotation to a worm wheel 8 fast with a drum 9 on the surface of which are grooves 10 cut to correspond to the heads of the shells, so that when the head of a shell is pushed into a groove, the shell is supported and stands out radially from the surface of the drum as seen in Fig. 3.

The shells *s* fall from a mandrel 11, on which they are supported while being printed down a chute 12 and the lowest shell drops from the chute onto a table 13 in front of a pusher 14 reciprocated in guides 15 by a lever 16 rocked on its pivot 17 by a cam 18 on a vertical shaft 19 geared to the shaft 1. Each time that the lever is rocked the pusher pushes the lowest shell into that groove which happens to be opposite to it and also comes beneath the head of the next lowest shell and supports it until the pusher moves back, when this shell drops onto the table in front of the pusher. Thus as the drum rotates one shell is pushed into each groove and then a second shell is pushed into the first groove and itself pushes the first shell in that groove slightly along it and so on until eventually all the grooves are filled with shells throughout their length and then the shells which by this time are quite dry are pushed out of the grooves on the left of the drum and fall into some receptacle placed for them.

What I claim is:—

The combination of a drum having grooves formed on its surface, means for pushing articles into the grooves and means for rotating the drum.

HOWARD DOUGLAS HODGE.
